UNITED STATES PATENT OFFICE.

HARRY G. MOORE, OF PHILADELPHIA, PENNSYLVANIA.

DESIGN FOR A VEHICLE-BODY.

53,044.

Specification for Design.

Patented Mar. 4, 1919.

Application filed October 16, 1918. Serial No. 258,389. Term of patent 14 years.

To all whom it may concern:

Be it known that I, HARRY G. MOORE, a citizen of the United States, residing at Philadelphia, in the county of Philadelphia and State of Pennsylvania, have invented a new, original, and ornamental Design for a Vehicle-Body, of which the following is a specification, reference being had to the accompanying drawing, forming a part thereof.

The figure is a side elevation of a vehicle body, showing my new design.

I claim:

The ornamental design for a vehicle body, as shown.

HARRY G. MOORE.

Witnesses:

MARION H. CROWL,
HARRY BAUER.
